CLAIM

The ornamental design for a baseball oval helmet pad, as shown and described.

DESCRIPTION

FIG. 1 is a perspective view of a baseball oval helmet pad showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective environmental view thereof; and,

FIG. 9 is a rear perspective environmental view thereof. The broken lines illustrate unclaimed portions of the article or portions of the environment and form no part of the claimed design.

1 Claim, 5 Drawing Sheets
